(57) **CLAIM**

The ornamental design for a water bottle with handle straw lid, as shown and described.

DESCRIPTION

FIG. 1 is a left side view of a water bottle with handle straw lid showing my new design;

FIG. 2 is a right side view thereof;

FIG. 3 is a rear side elevation view thereof;

FIG. 4 is a front side elevation view thereof;

FIG. 5 is a top elevation view thereof;

FIG. 6 is a bottom elevation view thereof; and,

FIG. 7 is an exploded perspective view thereof.

The broken lines in the figures illustrate portions of the water bottle with handle straw lid that form no part of the claimed design.
